UNITED STATES PATENT OFFICE.

JOHN WILLIAM HUNTER, OF MACON, MISSISSIPPI.

BALING-PRESS.

SPECIFICATION forming part of Letters Patent No. 406,046, dated July 2, 1889.

Application filed December 31, 1888. Serial No. 294,990. (No model.)

To all whom it may concern:

Be it known that I, JOHN WILLIAM HUNTER, a citizen of the United States, residing at Macon, in the county of Noxubee and State 5 of Mississippi, have invented new and useful Improvements in Baling-Presses, of which the following is a specification.

My invention relates to improvements in baling-presses; and it consists in certain novel 10 features hereinafter described and claimed.

In the accompanying drawings, Figure 1 is a side view of a press constructed in accordance with my invention. Fig. 2 is a horizontal section; and Fig. 3 is detail view in perspective of the re-enforcing plates forming the connection between the power-lever and the pitman. Fig. 4 is a detail perspective 15 view of the end of the power-lever.

Referring to the drawings by letter, A designates the frame of the press provided with an open rear end and having its sides open in their rear portion. The baling-chamber B is provided at a proper point of the frame and has a feed-opening C in its top, through which 20 the hay is fed into said chamber. The sides of the baling-chamber are provided with longitudinal slots D, and in said slots I pivot the triggers or dogs E, the rear ends of which are bent abruptly inward to provide the shoulders F, and are provided with the downwardly- 25 turned lips or hooks G, which are adapted to engage with the sides of the baling-chamber to prevent the triggers or dogs passing too far into the chamber. To the outer side of the 30 frame I secure the bars H, to which springs I are attached, the said springs bearing upon the triggers or dogs to force them normally into the baling-chamber. The power-lever J is pivoted in the front end of the press, and 35 is connected with the plunger K by the pitman L. The plunger moves in the frame of the press, and is provided at its rear ends at its sides with the recesses M, which receive the ends of the dogs or triggers E, 40 when it has been forced inward to form the bale. The pitman is pivoted to the front end of the plunger, and is provided at its front end with a casting N, which fits between the 45 rear ends of the re-enforcing plates O, secured 50 to the lever, and receives the pivot-pin P, which is passed vertically downward through

the ends of the said re-enforcing plates and the end of the casting N. The re-enforcing plates are provided on their opposing faces with the ribs Q, substantially U or V shaped, 55 which engage the similarly-shaped recesses or notches R in the end of the lever, so as to aid in holding the said plates in position, and also provide a wearing-surface adapted to receive the contact of the pitman when the lever has been carried to the limit of its stroke. These ribs and notches, by engaging in the manner described, effectually prevent the re-enforcing plates slipping upon the power-lever, and the said plates are consequently 60 securely held to the lever, so as to strengthen and brace the same at the point where the greatest strain is applied thereto. The king-bolt or fulcrum-pin is passed downward through the front end of the frame of the 65 press, through the re-enforcing plates and the end of the lever to secure the lever in position.

In practice the hay or cotton is placed in the baling-chamber, and the lever is then carried around from side to side, causing the pitman to be oscillated, so as to reciprocate the plunger within the press. As the plunger is forced inward the hay will be compressed and pushed from the baling-chamber. As the 70 hay which has been formed into a bale leaves the baling-chamber the triggers or dogs will be forced into the baling-chamber by the springs bearing thereon, so as to prevent the pressed material flying back into the baling- 75 chamber by reason of its expansion after the plunger has been withdrawn. The recesses in the end of the plunger allow the same to be forced inward to the full extent of its stroke 80 without interfering with the action of the said 85 dogs or triggers.

My improved press is very strong and durable, and is efficient in its operation. The re-enforcing plates at the ends of the lever strengthen the same at the point where the 90 greatest strain is applied thereto, and also reduce the wear of the parts by providing metal surfaces at all the points of contact.

Having thus described my invention, what I claim, and desire to secure by Letters Patent, is—

The combination, with the frame and the

plunger, of the pitman pivoted to the plunger, the casting secured to the end of the pitman, the power-lever, the re-enforcing plates secured to the ends of the lever and having 5 **U** or **V** shaped ribs on their opposing faces engaging recesses in the ends of the lever, the pivot-pin passed through the ends of the re-enforcing plates and the casting secured to the pitman, and the king-bolt passed through 10 the front end of the frame and through the

re-enforcing plates and the end of the lever, as specified.

In testimony that I claim the foregoing as my own I have hereto affixed my signature in presence of two witnesses.

JOHN WILLIAM HUNTER.
